UNITED STATES PATENT OFFICE.

ISAAC RITTER, JR., OF PHILADELPHIA, PENNSYLVANIA, ASSIGNOR TO
W. A. NEWMAN DORLAND, OF PHILADELPHIA, PENNSYLVANIA.

TOOL FOR FINISHING METAL SURFACES OR THE LIKE.

SPECIFICATION forming part of Letters Patent No. 700,825, dated May 27, 1902.

Application filed February 18, 1901. Serial No. 47,891. (No model.)

To all whom it may concern:

Be it known that I, ISAAC RITTER, Jr., a citizen of the United States, residing at No. 1816 Hamilton street, in the city of Philadelphia, county of Philadelphia, and State of Pennsylvania, have invented a new and useful Tool for Finishing Metal Surfaces or the Like, of which the following is a specification.

My invention relates to improvements in tools for finishing metal surfaces and the like; and the objects of my invention are, first, to provide two substantially parallel knives for scraping the surface to be finished; second, to support said knives so as to enable them to always adapt themselves to the surface to be finished, and, third, to provide means of securing said knives so as not to interfere with their action. I attain these objects by the mechanism illustrated in the accompanying drawings, in which—

Figure 1 is a side elevation of a tool embodying the main features of my invention, showing the tool attached to a boring-bar. Fig. 2 is a front elevation of the same. Fig. 3 is a side elevation of a modified form of the tool arranged for larger work and showing the tool adjustably mounted in a movable boring-bar head.

Similar letters refer to similar parts throughout the several views.

Referring to Figs. 1 and 2 of the drawings, *c* represents the support or axis for the tool *a*, and radially from the periphery or perimeter of this support *c* projects the bracket *d*, which is rigidly secured to said axis or support *c* by a bolt or other suitable fastening means. The tool *a* consists of a plate of preferably curved or arc shape, and from the exterior face of this plate projects one or more knives or scraping edges *a'*. One end of this plate is connected, preferably, by a link *e* to the bracket *d*, so as to permit the tool *a* to swing eccentrically to the support *c*. Where, as in the instance shown, the support *c* is a boring-bar, the tool *a* and its knives *a'* are normally concentric with the periphery of the bar *c*, but may swing toward or away from the periphery of the bar *c* by reason of the

flexible connection or link *e* between one end of the tool *a* and the bracket *d*. To maintain the tool *a* in normal concentric relationship with the support *c*, a resilient block *b* is interposed between the inner face of the tool *a* and the periphery of the support *c*.

In the modification illustrated in Fig. 3 the bracket *g* slides radially in a slot of the boring-bar *h* and may be fixed to the bar *h* when properly adjusted by bolts or other fastening means. The bracket *g* has a shoulder *g'* concentric with the periphery of the bar *h*, and between this shoulder *g'* and the back of the tool *a* the resilient block *b* is interposed. The tool *a* is connected to the end of bracket *g* by the same link connection *e* as hereinbefore used with the bracket *d* in the form illustrated in Figs. 1 and 2.

Having thus described my invention, what I claim as new, and desire to secure by Letters Patent, is—

1. In a tool of the character described, a support, a curved or arc-shaped tool provided on its outer face with cutting or scraping edges and normally arranged concentric with the periphery of the support, means for flexibly connecting one end of the tool to the periphery of the support so as to permit the tool to swing eccentrically to the support and resilient means interposed between the inner face of the tool and the support.

2. In a tool of the character described, a scraping-tool comprising a curved plate provided on its outer face with scraping edges, a central support, a resilient means interposed between the plate and the support, and a link for connecting one end of said plate to said support and thereby permitting the plate to swing eccentrically toward or away from the periphery of the support.

In testimony whereof I have signed my name to this specification in the presence of two subscribing witnesses.

ISAAC RITTER, JR.
